CLAIM

The ornamental design for a portable basketball system, as shown and described.

DESCRIPTION

FIG. 1 is a perspective view showing our new design for a portable basketball system together with related environment;

FIG. 2 is a close-up perspective view of the new design;

FIG. 3 is a front view thereof;

FIG. 4 is a side view thereof;

FIG. 5 is a rear view thereof; and,

FIG. 6 is a top view thereof.

The broken lines are included for the purpose of illustrating the portions of the portable basketball system and its environment that form no part of the claimed design. The appearance within the unshaded areas defined by solid lines within the center hub area of the wheels, the peripheral opening in the wheels, the round opening on the top of the system, the y-shaped area on the top of the system, and the recesses on the front of the system likewise form no part of the claimed design.
